GUN MOUNT FOR AEROPLANES

Application filed January 9, 1931. Serial No. 507,628.

This invention relates to an improved gun-mount particularly for swiftly moving carriers, such as aeroplanes, which create considerable windage by their motion. On an 5 aeroplane, for example, it is desirable to mount a gun so that it can be trained in various directions relative to the heading of the aeroplane and on either side thereof. To this end the gun may be swivelly mounted 10 on a support which, in turn, is rotatable about a vertical axis through the center line of the fuselage, the portion of the support carrying the gun being offset from the axis so as to present the gun on either side of the 15 aeroplane with the gunner behind it in operating position. With a gun-mounting of this type, lateral pressure of the wind on the gun itself is a disturbing factor tending to rotate the support on its axis when 20 the gun is trained broadside or in any direction other than fore and aft. This interferes with the free action of the gun mount which is essential for the effective operation of the gun. The drag of the gun on 25 one side or the other of the aeroplane, unless suitably counteracted, seriously affects the steering of the aeroplane itself. This is especially true of guns which are provided with a shield for the protection of the gunner. 30 According to the invention counteracting means such as a vane is mounted on a bracket on the rim of the gun-mount opposite to the gun to present a resisting surface to the wind to offset the pressure on the gun itself. 35 As different makes of machine guns present different resisting surfaces to wind pressure, the balancing vane may be made adjustable so as to balance any make of machine gun. 40

For a more complete understanding of the invention, including additional advantageous features, reference may be had to the description thereof which follows and to the 45 drawings, of which,—

Figure 1 is a perspective view of an embodiment of the invention as it might appear installed in an aeroplane.

Figure 2 is a side elevation of a gun-mount 50 embodying the invention, portions being bro-

ken away to show the inner parts in section.

Figure 3 is a sectional detail of a portion of the mechanism shown in Figure 2.

Figure 4 is a section on the line 4—4 of 55 Figure 3.

Figure 5 is a section on the line 5—5 of Figure 2.

Figure 6 is an elevation showing a modified mounting for a vane. 60

The invention may be embodied in a rotatable mount 10 which has a central cylindrical tube 11 surrounding and bearing on a fixed post 12, the latter being securely mounted on the framework of the aeroplane. 65 The mount 10 also includes diametrically opposed portions laterally offset from the central tube 11 to support a gun and a vane respectively. The mount 10 as a whole may be in the form of a cup, as shown, the gun and vane being supported on opposite portions of its rim. The mount 10 may be nested within a larger cup-shaped receptacle 13, from the walls and bottom of which it is suitably spaced. The top of the post 12 may have a circular plate 14 to which is rigidly attached an inner cup-shaped member 15 which serves as a cockpit for the operator of the gun. The cockpit 15 has a central hollow column 16, the top of which is secured directly to the plate 14. The column 16 may support a suitable seat 17 projecting from a ring 18 which encircles the tubular member 16. The seat ring 18 preferably rests on ball bearings carried by a supporting ring 20 which is adjustably fixed on the column 16 by a set screw or otherwise. A retaining ring 19 may also be mounted on the column 16 just above the seat ring 18. 70 75 80 85

It is desirable that the gun-mount 10 be 90 capable of free rotation so as to facilitate the training of the gun in any desired direction. To this end suitable roller bearings or ball bearings 22 may be provided between the lower portion of the post 12 and the tubular portion 11 of the mount, and a second ball bearing 23 may be employed between the upper portion of the post 12 and the tube 11. A third ball bearing 24 may also be provided between the lower portion of the tube 11 and the 95 100

column 16. These bearings take the lateral thrusts arising from any tilting of the aeroplane and permit the ready rotation of the mount 10 when the aeroplane is in any position whatever. To retain the ball bearings 23 in place, a suitable cone, with check nuts to permit adjustment, may be mounted on the post 12. Fixed to the upper rim of the mount 10 is a swivel standard 30 which carries a machine gun 31 or other equivalent weapon.

In order to counterbalance the wind pressure on the gun 31, a vane may be mounted on the rim of the mount 10 at a point diametrically opposite the gun 31. A single plate is found to be unsuitable for this purpose since it is usually presented at an angle to the direction of motion of the aeroplane. It thus acts as a rudder, causing a powerful lateral draft and seriously interfering with the guidance of the aeroplane. According to the present invention, a vane is provided which offers the desired resistance with the minimum resultant lateral draft. To this end a post 32 may be outwardly offset from the rim of the mount 10 as by a bracket 33 so that the vane will not interfere with the operator. Swivelly mounted on the post 32 is a vane consisting of a bearing sleeve 34 fitted in the post, and a pair of vertical plates 36 and 37 each swivelly mounted along one edge on the sleeve 34 and adjustable toward and from each other. Thus the vane, as a whole, swings on the post 32 as an axis, the post as illustrated being at the intersection of the planes of the plates 36 and 37. In order to adjust the wind resistance of the vane, means is provided for holding the two plates in adjusted relative angular position. To this end a supporting bar 38 is fixed to and projects laterally from the bearing sleeve 34, this bar carrying a ratchet quadrant 40, the teeth of which are engaged by a detent 41 mounted on a hand lever 42 which is pivoted as at 43 at the center of curvature of the ratchet quadrant 40. The lever 42 is provided with a pair of ears 44, 45 which are connected respectively by links 46, 47 to similar ears 48, 49 on the plates 36 and 37. It is apparent that when the lever 42 is swung toward the post 32, this motion will cause the plates 36, 37 to swing apart forming a larger angle between them. This increases the wind resistance of the vane, since the vane as a whole is free to swing away from the wind and thus always heads into the wind.

The vane as a whole need not be pivoted at the intersection of the plates, but may be pivoted elsewhere as shown, for example, in Figure 6. In this form, the post 32 may project through the bar 38 at a point laterally spaced from the line of intersection of the plates. In such case the bar 38 may be provided with an extension 39 extending up through the hinge members of the plates 36 and 37, and then

rearwardly to pivot on the upper end of the post 32.

It is desirable to secure the gun-mount releasably in any position of rotational adjustment. For this purpose a rail 50 may be mounted on the inside wall of the receptacle 13. The rail 50 is provided with ratchet teeth 51 along its upper edge and similar teeth 52 along its lower edge. Engaging these teeth, respectively, are a pair of pawls 53 and 54, these pawls being rockably mounted on pins 55 and 56 projecting outwardly from the cylindrical wall of the mount 10. A bell-crank 60 may be provided to disengage the pawls from their ratchets when it is desired to swing the gun-mount 10 to a different angular position. Two arms of the bell crank 60 are provided with pins 61, 62 which enter respectively slots 63 and 64 in the pawls 53 and 54. These slots are arranged in such a way, as shown in Figure 4, that when the arms of the bell-crank 60 are swung in one direction, the pawls 53 and 54 are held in engagement with the teeth of their respective ratchets. When the bell-crank 60 is swung in the opposite direction, the pawls 53 and 54 are moved clear of their ratchets. The third arm 65 of the bell-crank may be connected to a rod 66 which is movable downwardly by pressure on a knob 67 at its upper end to release the pawls 53 and 54 from their ratchets. The operating knob 67 is preferably located to the left of the gun so as to be easily operable by the left hand of the gunner while his right hand is being used in the operation of the gun. The rod 66 is normally held in its uppermost position as by a spring 68 which is compressed between the knob 67 and the upper rim of the gun-mount 10 through which the rod passes.

The arrangement of three concentric cups affords considerable protection both to the gunner and to the bearings of the mount. The latter are contained within a narrow column on a spindle, and do not offer much of a target. The bearings are furthermore protected by five walls from lateral fire so that it would be difficult for an enemy to put the mount out of commission. The protection of the bearings is of vital importance as in aeroplane fighting, the gun must frequently and quickly be swung from one side to the other.

It will be evident to one skilled in the art that many modifications and changes can be made in the specific embodiment of the invention herein shown and described without departing from the spirit and scope thereof as defined in the following claims.

We claim:

1. Mechanism of the class described comprising a member pivotally supported to turn on a vertical axis, said member having portions extending laterally in opposite directions from said axis, a gun support on one of said portions, and a vane on the opposite

portion, said vane including a pair of surfaces making an angle with each other and pivotally supported at or near the apex of said angle.

5 2. Mechanism of the class described comprising a member pivotally supported to turn on a vertical axis, said member having portions extending laterally in opposite directions from said axis, a gun-support on one 10 of said portions, and a vane on the opposite portion, said vane including a pair of surfaces making an angle with each other and pivotally supported at the apex of said angle, and means between said surfaces for 15 holding them in adjustable angular relation to each other.

3. Mechanism of the class described comprising a cup-shaped receptacle having a central tubular member, a fixed supporting post 20 extending upwardly through said member, bearings on said post for supporting said receptacle, a gun-supporting bracket mounted on the rim of said receptacle, and a vane mounted on said rim diametrically opposite 25 to said bracket.

4. Mechanism of the class described comprising a cup-shaped receptacle having a central tubular member, a fixed supporting post extending upwardly through said member, 30 bearings on the sides of said post for supporting said receptacle, a cup-shaped cockpit nested in said receptacle and spaced therefrom, said cockpit having a central tube surrounding said tubular member and secured 35 to the upper end of said post, a gun-supporting bracket mounted on the rim of said receptacle, and means on said rim opposite said bracket for counteracting the wind pressure on a gun carried by said bracket.

40 5. Mechanism of the class described comprising a cup-shaped container, a central post fixed therein, a member pivotally supported on said post to revolve around the axis thereof, said member having portions 45 extending laterally in opposite directions from said axis, a gun-support on one of said portions, a wind resistance vane on the other said portion, and means for releasably locking said container and member against relative rotation.

In testimony whereof we have affixed our signatures.

ALEXANDER ALLAN.

WILLIAM HARRISON INNES.
